ALEXANDRE COMPAGNA, OF BIDDEFORD, MAINE, ASSIGNOR TO CROMPTON & KNOWLES LOOM WORKS, OF WORCESTER, MASSACHUSETTS, A CORPORATION OF MASSACHUSETTS.

BOBBIN-HOLDER DEVICE FOR STATIONARY MAGAZINES.

Application filed November 15, 1923. Serial No. 675,002.

To all whom it may concern:

Be it known that I, ALEXANDRE COMPAGNA, a citizen of the United States, residing at Biddeford, in the county of York and State of Maine, have invented new and useful Bobbin-Holding Devices for Stationary Magazines, of which the following is a specification.

This invention relates to automatic looms of the weft replenishing type in which a stationary weft carrier magazine is provided, having a plurality of separate bobbin or weft carrier compartments. In such looms, a certain kind or color of weft may be infrequently used, so that certain weft carriers may remain in the magazine for a long period of time. It has been found that the jar and vibration of the loom tends to produce slight angular movements of the weft carriers which in time may entangle the weft ends and cause breakage thereof upon transfer.

Devices and arrangements for preventing such angular movements have been heretofore proposed, but it is the object of my invention to improve the construction and operation of such devices so that advantageous results therefrom may be more effectively attained.

With this general object in view, one feature of my invention relates to the provision of weft carrier or bobbin holding devices of simple, substantial, and durable construction, each device preferably being formed from a single metal rod and extending vertically adjacent the bobbins in a particular magazine compartment. Provision is made for pressing these holding devices yieldingly against the sides of the bobbins or against the yarn thereon, thus restraining angular movement thereof.

Another feature of my invention relates to the release or withdrawal of the holding devices to permit free downward movement of the weft carriers upon indication of weft exhaustion and particularly to such release of the holding devices by the weft carrier supports or "cradles" by which the bobbins are retained in the magazine compartments.

A preferred form of my invention is shown in the drawings in which

Fig. 1 is a sectional side elevation of portions of a stationary weft carrier magazine embodying my improvements; 55

Fig. 2 is a plan view of the parts shown in Fig. 1; and

Fig. 3 is a detail sectional view, taken along the line 3-3 in Fig. 1.

Referring to the drawings, I have shown portions of a loom magazine comprising a magazine frame 10 forming one end of the magazine and provided with flanges 11 and ribs 12 by which the magazine is divided into a series of separate vertical compartments 13. The frame 10 is connected to a second frame member (not shown) by cross bars 14. This second frame member is similarly divided into vertical compartments 15 and is adapted to receive the tips of the bobbins in the usual manner. 60

The lowermost bobbin or weft carrier B in each compartment is retained in the compartment by a weft carrier support or cradle 15, pivoted at 16' (Fig. 3) on the magazine frame 10. This cradle 15 is provided with an enlarged supporting surface 16 which is concave on its inner face and convex outwardly and is adapted to receive and support the lowest bobbin when it is advanced 70 to intermediate position upon indication of weft exhaustion. Suitable actuating mechanism (not shown) is provided for rocking the cradles 15 to release the bobbins. 75

The parts thus far described are of the usual type and form no part of my present invention which relates particularly to the provision of bobbin holding devices 17, preferably each formed from a single piece of wire rod bent to an irregular U-shape. The short offset upper leg 18 of each holding device 17 is pivotally mounted in a bearing or bracket 19 supported in fixed position by the magazine frame 10. A coil spring 20 surrounds the part 18 of each holding device 95 17 and is secured at its lower end to the bracket 19 and at its upper end to a collar 21 adjustable on the part 18. 90

The spring 20 is so disposed that any desired tension may be applied to the holding 100 device to press the long straight vertical leg of the holding device against the sides of the bobbins B or of the yarn Y thereon. At its extreme lower end, each holding device

17 is provided with an offset projecting portion 24 positioned adjacent the enlarged portion 16 of its associated cradle 15.

When the cradles are in the normal position shown in full lines in Fig. 1, the bobbins or weft carriers are supported thereby and the holding devices 17 are moved yieldingly against the bobbins or the yarn thereon by the springs 20. If, however, one of the cradles is swung to the position indicated in dotted lines in Fig. 1, the portion 16 of the cradle engages the portion 24 of the holding device, pushing the holding device outward to the position shown in dotted lines in Fig. 1 and thus releasing lateral pressure upon the bobbins at the same time that downward feeding movement thereof is desired. As soon as the cradles are returned to normal position after the delivery of a bobbin, the holding devices are released for engagement with the remaining bobbins.

While I prefer to construct the bobbin holding devices for release by the cradles as above described, certain of the advantages of the holding devices may be independently utilized. Accordingly, I have indicated the holding devices 17^a for two of the compartments as having the lower ends shortened and the offset projecting portions omitted. These holding devices 17^a remain continuously in engagement with the bobbins in the magazine.

Having thus described my invention and the advantages thereof, I do not wish to be limited to the details herein disclosed otherwise than as set forth in the claims, but what I claim is:

1. In a loom, a weft carrier magazine having a plurality of weft carrier compartments, holding devices extending alongside said compartments and adjacent the weft carriers, and movably mounted members for supporting and releasing said weft carriers, said members directly engaging said holding devices and each member moving its associated holding device to inoperative posi-

tion when releasing a weft carrier from its magazine compartment.

2. In a loom, a weft carrier magazine having a plurality of weft carrier compartments, holding devices extending alongside said compartments and adjacent the weft carriers, and movably mounted members for supporting and releasing said weft carriers, each holding device having a portion thereof extending adjacent its associated supporting member and engaged thereby for movement to inoperative position upon weft carrier release by said member.

3. In a loom, a weft carrier magazine having a plurality of weft carrier compartments, holding devices extending alongside said compartments and adjacent the weft carriers, and movably mounted members for supporting and releasing said weft carriers, each supporting member having a contact portion and each holding device having a portion extending adjacent thereto, whereby said holding device may be moved to inoperative position upon release of a weft carrier by its associated supporting member.

4. In a loom, a weft carrier magazine having a plurality of weft carrier compartments, holding devices extending alongside said compartments and adjacent the weft carriers, each holding device being formed from a single piece of metal rod bent to substantially U-shape with one portion thereof pivoted on said magazine, and means to yieldingly press said holding device against the weft carriers in a magazine compartment.

5. A weft carrier holding device comprising a single metal rod bent to substantially U-shape, with its short upper leg forming a pivotal bearing for said device and with its lower end offset for engagement by a releasing device.

In testimony whereof I have hereunto affixed my signature.

ALEXANDRE COMPAGNA.
